WRAPPING-MACHINE FOR ROUND TABLETS.

1,259,475.

Specification of Letters Patent. Patented Mar. 19, 1918.

Application filed August 4, 1917. Serial No. 184,386.

To all whom it may concern:

Be it known that I, EMIL BAUMANN, a citizen of the Swiss Confederation, and residing at Berne, Switzerland, have invented 5 a certain new and useful Improved Wrapping-Machine for Round Tablets, of which the following is a specification.

My invention relates to a wrapping-machine for round tablets and is provided with 10 one constituent part for conveying the tablet together with a sheet of wrapping paper downward and through an opening into a position between at least three other parts supporting the tablet laterally, a ring capable 15 of a circular movement being provided above the three parts in such a manner as by means of its inner edge to have the paper projecting over and above the tablet folded down toward the center on the upper face 20 of the same.

In the drawing representing as an example of the object of my invention a twin wrapping-machine—

Figure 1 is a side elevation;

25 Fig. 2 a front view of one half of the machine seen from the right in Fig. 1.

Fig. 3 a plan,

Fig. 4 a part of a plan and

Fig. 5 a detail of the machine.

30 The machine as shown is provided with two magazines 3 and 4 placed alongside each other on a horizontal plate 1 of the machine frame 2, said magazines consisting of vertical tubes open at both ends and slotted vertically on the front side of the machine as at 5 so as to allow an easy control of the number of the tablets and to give access to the same. Plate 1 is resting on the upwardly turned flanges of a U shaped channel-like plate 6 which projects over plate 1 and reposes on two plates 7 by means of two fillets 6' provided at the ends of said plate 6. The inner surface between the two flanges of plate 6 serves as a path for a 35 slide 8 and for the tablets, the latter coming out from the bottom ends of the magazines and being pushed by the two ends of the slide forward from underneath plate 1. The flanges of plate 6 are only very little higher 40 than the top of slide 8 and of the tablets and therefore only one tablet at a time can leave the openings of the magazines.

By alternately moving to and fro the slide 8 which is the same for both magazines and 45 which has cut-out ends so as to suit the

shape of the tablets (Fig. 3) the latter are pushed alternately toward two openings 9 provided in the path of the slide. The slide 8 is operated by means of two levers 10 and 10' mounted on a horizontal shaft 60 11, lever 10 being engaged with a slide piece 12 fastened to slide 8 and lever 10' being pressed by means of a spring 14 attached to lever 10 against the face of a cam 13. This cam is fastened unto the face of a 65 grooved disk 15 and its free face is set obliquely with regard to shaft 11 so that the levers 10, 10' will move once to and fro for each revolution of the shaft pushing thereby one tablet each from underneath the 70 magazines 3 and 4. The distance between magazine 3 and opening 9 is so chosen that at the most two tablets at a time will find place in this space. In order to prevent the standing-up against each other of any two 75 tablets touching each other on account of the beveled edges of the same a weight piece 49 mounted so as to swing vertically on a pin 48 has been provided outside of plate 1 above the path of slide 8, said piece 49 80 reposing on the tablet or tablets resting on plate 6. Disk 15 on its face opposite cam 13 is provided with a groove 17 running partly concentrically with and partly eccentrically to shaft 16, said groove serving as 85 a guide for a friction roller fitted on the shorter arm of a bell-crank lever 18. The forked longer arm of the same engages with a pin 19 standing rigidly fast and at right angles on a vertical rod 20. To the upper 90 end of this rod is secured fast an arm 21 projecting over plate 6 and carrying within an eye over the opening 9 a hollow downwardly projecting rod 22 which is fitted at its lower end with a hollow bell-shaped head 95 23. The diameter of the same corresponds to that of the tablets, so that head 23 can be pushed through opening 9 and through an opening 24 below it provided within plate 7 and having a strongly rounded-off upper 100 edge.

A rod 25 fitted slidably within rod 22 bears with its top end 26 against a small spring 27 provided in a recess of the bore of rod 22 and is provided at its bottom end 105 28 with a disk-like head 28 as a means for pushing the tablets downward through the openings 9 and 24 of plates 6 and 7 respectively. Before a tablet passes opening 9 opening 24 is covered with a sheet of tin- 110

foil, or aluminum or the like intended as a wrapper for the tablet. The wrapping sheet marked 29 on the drawing is cut off from a continuously traveling band 37 by means of a knife 31 swinging up and down around a shaft 30. The knife is operated from a cam-roller 36 on the shaft 16 by means of a lever 33 mounted pivotally on the machine frame and by a link 32 connecting the same with the lever 32 fixed on the shaft 30. The contact between cam roller 36 and a friction roller fitted to the end of lever 33 is secured by a spring 34 engaging with lever 33. Band 37 unrolling from a roller 39 passes underneath a roller 40 wherfrom it is led upward over two rollers 41 and 41' and over a table 42 the front edge of which together with the knife 31 forms the cutter. Roller 40 is mounted on an axis 43 held fast at the end of a lever 44 and the latter is suspended by means of a traction member 44' affixed to one of the bearings of shaft 39 and running over said shaft so as to act like a brake on roller 39. A counter-weight 45 slidably supported by a lever 44 counterbalances the weight of roller 40 to such an extent that this roller touches the band 37 but slightly and keeps the same taut. A roller 46 provided on its circumference with a frictional covering and held within bearings 46' formed by vertical slots open at their tops rests above a companion roller. The cheeks of these slot-bearings are shortened on one side of the bearing exposing the trunnions. Alongside of the cheeks have been provided vertical pins 47 and levers 47' which are swingingly fitted thereonto and which may be shifted upward against the action of a spring 47''. These levers 47' extend over the lower cheeks and bear upon the trunnions of the roller 46 pressing the latter downward onto the band 37 thus clamping the latter between roller 46 and its companion roller. The roller 46 and its companion roller are in engagement by means of a gear 50, 51. The trunnion of the lower roller is fitted with the pinion 50 and carries at the end of a lengthened part a pinion 52 gearing with a toothed rim 53 of a friction ratchet gear not shown in the drawing. The ratchet gear having the toothed rim 53 is rocked back and forth by means of levers 54, 55 (Figs. 1 and 3) by a crank disk 56 mounted on shaft 16 for the purpose of exactly positioning the band 37 during the operation of the cutter 31. Moreover a lever 57 is provided (Fig. 2), which at its lower end carries a friction roller bearing against a cam 58 also mounted on shaft 16 (Figs. 2 and 5). At its upper end lever 57 supports one of the trunnions of the lower companion roller referred to. During the cutting operation which in fact lasts but an instant the cam disk 58 will move lever 57 in a sense

opposite to the ordinary turning direction of the companion roller. At the same time the rotation of this roller is interrupted while the friction ratchet gear is swinging back for the next feeding movement. Roller 41 will be turned back for such an amount only that the cut off edge of the band will be moved back a little from the knife during the latter's upward stroke. Four vertical shafts 59 carrying each a roller 60 above a horizontal plate 2' of the machine frame are grouped around the lengthened axis of the registering openings 9 and 24. The distance between the circumferential edges of each two diametrically opposed rollers is somewhat greater than the diameter of the tablets to be wrapped, so that the tablet together with its wrapping sheet brought down through the openings 9 and 24 will find room enough between the four rollers. In order to prevent the tablet from dropping through the rollers 60 and to cause it to stay for some time between the said rollers, these are provided at their lower circumferential edges with flanges 61 with a cut-out therein for letting pass the tablet after its being wrapped. Above the rollers 60 a horizontally placed ring 62 is linked on one side by means of an arm 63 to a lever 64 and on the other side by means of an arm 63' to a connecting rod 65 arranged crosswise to said arm (Fig. 4, lower part). Lever 64 is fixed to the top end of a vertical shaft 66 journaled on the outside of the machine frame and fitted at its bottom end with a crank 69 which by means of a spring 67 is pressed against the outer face of a cam disk 68 fast on shaft 16. The operating surface of this cam disk has two steps 68' and 68'' wherof the first is but half as high as the latter but very much larger. Ring 62 will therefore travel in the direction of the arms 63, 63' with two movements which are separated from each other by an interval of time and wherof the first will adjust the ring 62 at least approximately concentrically with the opening formed by the four rollers 60 and the second (according to the lower part of Fig. 4) will move the ring 62 so much toward the interior that its outer edge will reach into the interior of the said opening. The connecting rod 65 is guided on one side by means of a pin 71 engaging in a slot 70 cut into said rod and is linked on the other side at the upper end of a two armed lever 73 pivoted at 72. The pulling action on rod 65 exerted by a spring 74 causes the friction-roller at the lower end of lever 73 to bear against the circumference of disk 68 and of ring 62 and against the depression 75 there-in. This depression is so arranged with regard to the higher step 68'' of cam disk 68 that both will act simultaneously on their respective levers 69, 73. This will cause 130

the ring 62 to execute a composite movement which in the case as represented is approximately a semi-circular one. By this movement of ring 62 the portion of the wrapping sheet projecting above the upper side of rollers 60 is caused to be folded down at least partly toward the center of and over the tablet. The rollers 60 rotating all in the same sense are driven synchronously by shaft 16. This shaft is coupled by means of a chain gear 76 with a shaft 77 which by means of bevel gears 78 is driving a vertical shaft 79 arranged centrally with regard to shafts 59. Pinions 80 provided at the bottom ends of the shafts 59 are in gear with a common gear wheel 81 fixed at the top of shaft 79.

By the rotation of the rollers 60 the tablet held between the same will be rotated likewise which will cause the inward folding of the wrapping sheet on its whole circumference. In the position of the rollers 60 as shown in the upper portion of Fig. 4, one tablet will be dropped between the rollers and according to the position shown in the lower portion of Fig. 4, the tablet will be dropped through between the rollers which in this position have turned their cut-out portions 61' toward each other. In order to secure a quick and safe passage of the dropped tablets the cut-outs 61' are much enlarged toward the lower outlet so that the dropped tablets will even receive a downwardly directed blow from the rollers. The tablet being wrapped completely will after leaving the rollers be dropped into an inclined chute 82 gliding downward therein. In the path of the chute 82 are provided two rollers 83 and 84 arranged with their axes one above the other in an oblique plane and both made of elastic material. The first roller is driven from shaft 16 by means of gears not shown in the drawing for clearness's sake. The tablets gliding down the chute 82 will be seized between the said rollers 83 and 84 and on their passage between the same will have the folds of the wrapping sheet firmly pressed down. This will complete the whole wrapping operation.

The working of one half of the machine is as follows: A tablet after having left for instance the magazine 3 will be pushed by slide 8 within the channel-like plate 6 toward opening 9. At the same time band 37 has been fed toward opening 24 for a length amounting to the length of a wrapping sheet. Knife 31 will then swing downward at once swinging back and will have separated thereby a length of band 37 corresponding to the size of a wrapping sheet. The tablet being dropped now on this sheet will be pushed downward through the opening 24 by means of the downwardly moving heads 23, 28. By this operation the

parts of the wrapping sheet projecting over the tablet will be bent upward. The elastic suspension of the head 23 has the advantage that this head while moving again upward may yield to some extent 70 without taking the tablet along with it in the case that the sheet should be clamped between the head and the edge of opening 24. The tablet is then dropped through the ring 62 between the rollers 60, which will 75 begin to rotate the tablet. During this rotation ring 62 will move in an opposite sense with a circular movement (see the arrow in lower part of Fig. 4) and will fold the upwardly projecting edges of the sheet toward the inside and over the tablet. As soon as the cut-outs 61' of the rollers 61 come opposite each other the completely wrapped tablets drop into the chute 82 where gliding downward they are compressed between the rollers 83, 84, which 85 finish the wrapping operation.

The two halves of the machine work alternately. Slide 8 pushes the tablets from both magazines 3, 4 successively toward the 90 openings 9. Then one of the heads 23, 28 rises, while the other descends. During this operation a tablet is wrapped by one set of rollers and coöperating ring, while by the other set a wrapped tablet is dropped into 95 the chute 82, another tablet always immediately taking the place of the preceding tablet.

The construction of the machine as shown is, of course, capable of modifications which 100 still fall within the scope of my invention.

Claims:

1. In a wrapping machine for round tablets the combination with suitable feeding mechanisms for the tablets and the wrapping sheets therefor and with an opening leading to a folding device, of means for pushing a tablet placed on a wrapping sheet downward through the said opening thereby bending-up the projecting edges of 105 the sheet, means comprising at least three holding devices for maintaining the tablet in position laterally and a ring provided above the thus maintained tablet and underneath the said opening and capable of 110 bending the edges of the sheet together and down inwardly over the top face of the tablet.

2. In a wrapping machine for round tablets and the like, the combination with a tablet magazine, a feeding means for the tablets and a feeding means for the wrapping sheets, of means for delivering one tablet at a time to a delivery opening to be deposited 120 in said opening on a wrapper previously placed by the said wrapping sheet feeding means over a second opening registering with the said delivery opening, a device for pushing the tablet and wrapper together 125 130

through the said second opening, thereby bending up the projecting edges of the wrapping sheet, a grooved cam disk and a bell crank lever coöperating therewith for operating said pushing device, the latter comprising a hollow rod, a bell-shaped head thereon fitting the said openings and a rod mounted within said hollow rod and provided with a disk-like head adapted to 10 operate with said bell-shaped head.

3. In a wrapping machine for round tablets the combination with a feeding device for the tablets and a feeding device for the wrapping sheets, and actuating means there- 15 for for feeding the tablets and wrapping sheets toward two registering openings, of means for maintaining the tablet in position laterally after its passage through the delivery opening and the second opening registering therewith, means for bending the wrapper upwardly, means for folding the upwardly bent portions of the wrapper inwardly toward the center of the tablet and down on its upper face, said means comprising 20 a ring capable of a component movement, an arm on said ring, a lever for moving said ring by means of said arm in one direction, a shaft carrying said lever, a crank mounted on said shaft, a stepped cam disk coöperating with said crank, a second arm on said ring opposed to said other arm, a connecting rod coöperating with said sec- 25 ond arm, a two-armed lever, a cam for mov-

ing said lever, a spring yieldingly holding said lever in contact with said cam, and 35 means for operating said cam to actuate said lever in timed relation to said crank.

4. In a wrapping machine for round tablets and the like, the combination with separate feeding devices for the tablets and the 40 wrapping sheets and means for actuating said feeding devices, of a pushing device for pushing the tablet together with a wrapping sheet through an opening, thereby bending up the projecting portions of the 45 wrapping sheet placed by its feeding device below the tablet and over said opening, and a device for receiving and rotating the partly wrapped tablet to fold the wrapping sheets toward the inside and maintaining it 50 in position laterally the said device comprising rollers, rotatable shafts carrying the same, gear wheels mounted on said shafts, an actuating shaft, a gear wheel thereon in mesh with the gear wheels on the said roller 55 carrying shafts, a bevel gear on said actuating shaft, a horizontal driving shaft, and a bevel gear thereon in mesh with the bevel gear on said actuating shaft.

In testimony whereof, I affix my signature 60 in the presence of two witnesses.

EMIL BAUMANN.
